United States Patent Office

Des. 184,401
Patented Feb. 10, 1959

184,401

FURNITURE GLIDE

David R. Knowlton, Beverly, and Julius B. Wilhelm, Nantasket, Hull, Mass.

Application October 6, 1958, Serial No. 52,874

Term of patent 14 years

(Cl. D10—6)

Fig.1.

Fig.2.

Fig. 1 is a top plan view of a furniture glide embodying our new design; and

Fig. 2 is a view in side elevation of the furniture glide of Fig. 1.

We claim:

The ornamental design for a furniture glide, as shown.
